UNITED STATES PATENT OFFICE.

GEORGE L. CRAGG, OF CHICAGO, ILLINOIS, ASSIGNOR TO HARRY A. DOUGLAS, OF BRONSON, MICHIGAN.

LOCKING MECHANISM.

Application filed November 9, 1925. Serial No. 67,882.

My invention relates to locking mechanism and is of particular use in conjunction with combined switches for governing the ignition or power controlling circuits and the 5 lighting circuits of automotive vehicles and which combined switches employ switch handles for controlling the lighting circuits and locks for controlling the ignition or power controlling circuits. A prior switch of this 10 class is provided with an enclosing casing for the contacting mechanism, this casing having a central tubular portion projecting outwardly beyond the casing into the hollow hub of the lighting circuit controlling handle. This tubular casing portion that is 15 surrounded by the hub of a handle also constitutes a hollow member of the lock. This hollow lock member encloses a tumbler barrel that carries a number of tumblers movable transversely of the hollow lock member 20 and tumbler barrel and which enter openings formed in opposite sides of the hollow lock member after the tumbler barrel is turned by the inserted key to bring the tum- 25 bblers into register with said openings and in consequence of the withdrawal of the key following this turning movement of the tumbler barrel, the tumbler barrel being locked in fixed relation with the hollow lock 30 member when the tumblers enter the openings in this member. When the key is inserted to withdraw the tumblers from said 35 openings, the tumbler barrel may be turned by the inserted key to remove the tumblers 40 from alignment with the openings to bring the tumblers out of locking relation with the hollow lock member, imperforate portions 45 of this member then holding the tumblers out of locking relation with it. The 50 tumbler barrel is in operating relation with the contact actuator with the casing that governs the ignition circuit. When the key is inserted and turned to turn the tumbler barrel to an unlocked position, the ignition circuit is consequently closed. When the 55 key is reversely turned, the tumbler barrel is reversely turned, and the ignition circuit is consequently opened, the tumblers then being in register with the openings in the hollow lock member. When the key is withdrawn following its reversed turning movement, the tumblers are free to enter the 60 openings in the hollow lock member to lock the ignition circuit open.

In these prior switches, the tumbler barrel

or rotatable lock member was so positioned with relation to the handle as to require a deep hollow hub for the handle.

It is the general object of my invention to provide an improved locking mechanism for 60 locking the ignition switch in ignition circuit opening position and which also preferably enables the employment of a handle with a very shallow hub. In the preferred embodiment of the invention the locking 65 mechanism is inclusive of a tumbler barrel which is in fixed relation to the front casing end wall to be stationary instead of rotatable and which contains tumblers that are desirably disposed longitudinally of the axis of 70 the tumbler barrel. The tumbler barrel is formed to receive spring-pressed holding pins carried by a rotatable shell or hollow lock member that is mounted to turn upon the axis of the tumbler barrel and about the 75 barrel that preferably serves as a shaft upon which the hollow lock member is journaled. These pins are in their holding positions when the ignition circuit is to be locked 80 open.

In carrying out my invention in the preferred way, I provide a handle operated, light circuit controlling contact actuating ring within the switch casing, a second contact actuating ring surrounded by the first 85 and in controlling relation to the ignition circuit and operable directly by the tumbler barrel enclosing hollow lock member which is surrounded by the rings.

The invention will be more fully explained in connection with the accompanying drawings in which Fig. 1 is a front view of the preferred embodiment of the invention; Fig. 2 is a rear view; Fig. 3 is a sectional view on line 3-3 of Fig. 1, on 90 a larger scale; Fig. 4 is a sectional view on line 4-4 of Fig. 3, on a smaller scale; Fig. 5 is a sectional view on line 5-5 of Fig. 3; Fig. 6 is a sectional view on line 6-6 of Fig. 3; Fig. 7 is a sectional view on line 95 7-7 of Fig. 6; Fig. 8 is a sectional view on line 8-8 of Fig. 3; Fig. 9 is a sectional view on line 9-9 of Fig. 4; Fig. 10 is a sectional view on line 10-10 of Fig. 9; Fig. 11 is a perspective view showing two complementary parts of the lock mechanism in separated relation; Fig. 12 is a perspective view showing the hollow lock member and a portion of the casing end wall through 100 which it is passed; Fig. 13 is a perspective 105 view showing the hollow lock member and a portion of the casing end wall through which it is passed; Fig. 14 is a perspective 110 view showing the hollow lock member and a portion of the casing end wall through which it is passed.

view of a member fixed within the hollow lock member; Fig. 14 is a diagram of one circuit arrangement; and Fig. 15 is a perspective view of the preferred form of tumblers.

The switching mechanism to be later described is enclosed within a casing that is preferably cylindrical. The casing is desirably formed of sheet metal and has one end wall 1 integrally formed with its cylindrical wall 2. The other end wall of the casing is illustrated in the form of a contact carrying disc 3 of insulating material, this disc having bayonet pins 4 which are received in bayonet slots 5 formed in the casing wall 2. The end wall 3 thus constitutes a removable closure affording access to the interior of the casing for the purpose of locating the operating parts of the switching mechanism therein and for the inspection and replacement of these parts. The disc is held in assembly with the casing by spring pressure exerted rearwardly thereon and furnished by spring-pressed contacts, later to be described, that are contained in the casing. As will more fully appear, some of these spring-pressed contacts are supplemental to contacts 6, 6', 7, 8, 8', 9, 9', 9" and 10 carried by the closure disc 3 and other of these spring-pressed contacts are complementary to and engageable with the contacts 11 and 12 also carried by the disc 3. The contacts 13, 14, 15 and 16, that pertain to the contacts 6, 6', 7, 8, 8', 9, 9', 9" and 10, are in the nature of bulging formations formed in a ring 17, this ring and these contacts being diagrammatically indicated in Fig. 14. The contacts 18 and 19 that pertain to the contacts 11 and 12 are also in the nature of bulging formations which, in the case of these contacts, are formed in a metallic triangular contact carrying plate 20 surrounded by ring 17.

The particular nature of the circuits controlled by the handle and lock is not germane to my invention and, therefore, the circuit arrangement in Fig. 14 need not be particularly described. It will suffice to say that the switching arrangement illustrated is such that the lighting switch handle, when adjusted to parking position or an off position, establishes gaps in the ignition circuit so that this circuit may not then be closed but is free to be closed when the lighting switch is adjusted to "day," "dim," or "bright" positions.

The metallic ring 17 and metallic plate 20 are pressed toward the contact carrying disc 3 in order that the contacts on said ring and plate may press against the complementary contacts on the carrier 3 or on the insulation between these contacts, according to the circuit adjustment desired. The desired spring pressure is exerted by preferably providing each of the contacts 13, 14, 15 and 16

on the ring 17 and the contacts 18 and 19 and the corner portions 21 and 22 of triangular plate 20 with the spring devices such as those illustrated most clearly in Fig. 3. Each spring device includes a spring barrel 23 which houses a spring 24 and which presses the element (17 or 20) carrying it, toward the contact carrier 3. The springs 24, in the construction illustrated, carry no essential parts of the currents. The spring barrels 23 constitute means for flexibly coupling the contact carriers 17 and 20 with the actuators for these contact carriers. The actuator for the contact carrying plate 20 is desirably in the form of an insulating ring 26 which is coaxial with the casing. The actuator for the ring 17 is desirably in the form of another insulating ring 28 coaxial with and surrounding ring 26. The spring barrels 23 carried by the contact carriers are slidably received within recesses 27 formed in their actuating rings. As the ring 26 is turned, by my improved means which will later be described, the contact 18 on the plate 20 will ride into and out of cavities formed in the contact 11 and in the insulating contact carrying disc 3, the extent to which the ring 26 is spring-pressed away from the disc 3 being limited by its engagement with the casing end wall 1. Contact 12 is coaxial with the ring 26 and constantly holds contact 19.

The bore of the ring 28 has radially disposed enlargements 29 which receive the prongs 30 formed upon the hub portion 31 of a handle 32 and which project through arcuate slots 33 formed through the end wall 1 and concentric therewith. A plate 34, preferably circular and slightly dished, is suitably assembled with the casing end wall 1 upon the exterior thereof, as by means of rivets 35. The plate 34 may, if desired, constitute the mounting plate for the switch structure in which event it may be formed with screw receiving holes 34'. The handle hub 31 has a circular flange portion 31' that is concentric with the casing and which directly carries the prongs 30. This circular portion 31' is in the nature of a flange offset with respect to the body portion of the hub surrounded thereby to form an annular shoulder 36 concentric with the handle and casing and engaging the inner edge of the circular opening formed in the plate 34 concentrically with the handle and casing. The flange 31' is received in the space between the plate 34 and the casing end wall 1, the flange being in engagement with both plate and end wall at its circular edge to restrain the handle from movement along the casing axis. The shoulder 36 and the surrounding plate 34 confine the handle to turning movement upon the axis of the casing. The range of oscillation of the handle is defined by the lengths of the arcuate slots 33, this

range of movement being sufficient to enable the handle to turn the contact actuator 28 in either direction and to a sufficient extent to close the selected lighting circuit or to open all lighting circuits.

The contact actuator 26 that determines the position of the contact carrying plate 20 is, in the embodiment of the invention illustrated, held from movement, when the ignition circuit is to be locked open, by a stationary lock tumbler barrel 37 which is confined within the hollow rotatable lock member 38 which is in line with the axis of the handle. The tumbler barrel is provided 15 with arcuate recesses 39 which receive the arcuate wings 1' that extend inwardly from the casing end wall 1 into the lock receiving opening 1² formed in said wall, said wings preventing the tumbler barrel from turning.

20 The stationary tumbler barrel is mainly within the casing and serves as a journal for the rotatable hollow member 38 whose inner end is within the casing and in the zone of the actuating ring 26 that surrounds it. The rotatable hollow lock member 38 is 25 formed with transverse openings 40 which receive the base or connected end portions of the wings 1', it being the inner unattached ends of these wings that are received in the arcuate recesses 39 in the tumbler barrel. The openings 40 are of such extent as to permit the member 38 to be turned throughout the required range. The member 38 carries 30 side pins 38' that enter slots or openings 26' in ring 26, whereby this ring may be turned. These pins and openings are within the casing and afford sliding connection between the ring 26 and member 38. The outer end 35 of member 38 projects through the casing end wall opening 1' and through the lock opening 32' in the hub portion of the handle. A key opening 41 is formed in the side and outer end of member 38 and in line with a key guide way 42' in a key guide 42 that is secured within the outer end of member 38. A suitable key 43 is receivable in the key opening 41 and guide way 42' and is bodily swung to turn member 38. The invention is not to be limited, however, to 40 the bodily swinging movement of the key nor to the location of the key opening 40.

The tumblers 44 are employed to hold the rotatable hollow lock member 38 and the contact actuating ring 26 from rotation.

45 These tumblers are desirably arranged longitudinally of the axis of the stationary tumbler barrel 37 and are slideable within channels formed in the tumbler barrel along its axis. These tumblers serve to remove the holding pins 45 from the tumbler channels when the key is inserted, preparatory to the rotation of the member 38 from the position in which the ignition circuit is locked open to the position in which the ignition circuit is closed, said holding pins being

free to enter the tumbler channels when the hollow member is restored to circuit opening position and the key is withdrawn, said pins then serving to lock the ignition circuit open. The locking pins 45 are arranged in 70 channels that are formed in a pin carrier 46 which is secured to the inner end of the hollow lock member 38 to turn therewith, the channels in the carrier 46 that contain the pins 45 constituting continuations of the 75 channels in the tumbler barrel when the pin carrier is turned to circuit opening position. Springs 47 press outwardly upon the pins 45 so that when the channels in the pin carrier and tumbler barrel are aligned and the key 80 is withdrawn, the locking pins will enter the tumbler channels to a limited extent and without being ejected from the channels in the pin carrier whereafter the pin carrier and rotatable hollow member 38 cannot be 85 turned. The tumblers 44 are formed of T shape to afford transversely elongated heads to remain in engagement with the key throughout the bodily swinging movement 90 of the key.

The pin carrier is provided with a reduced outer end portion 45 that enters a socket 46 on the inner end of the tumbler barrel. The pin carrier and rotatable member are thus more positively aligned. The pin carrier 95 and the outer end of the lock member 38 thus have a fixed axis of rotation that includes the centers of the handle opening 32' and the opening 1' in the end wall 1. The handle opening 32', the casing opening 1' 100 and the bore of the lock member 38 are thus in register and coaxial with the tumbler barrel, the contact carriers 17 and 20 and the actuating rings 26 and 28.

The contact carriers 17 and 20, being 105 adapted to turn, serve as actuators in direct adjusting relation to the contacts carried thereby. The rings 26 and 28 serve as actuators for said contact carriers and, through these carriers, as actuators for said contacts. 110

Changes may be made without departing from the invention.

Having thus described my invention, I claim:

1. The combination with a casing; of a 115 tumbler barrel carried by an end wall of the casing and projecting into the interior of the casing; a hollow rotatable lock member journaled upon the tumbler barrel; a tumbler disposed longitudinally of the tumbler barrel and movable in a channel formed in and extending longitudinally of the tumbler barrel; an outwardly spring pressed holding pin carried by an inner portion of said hollow rotatable lock member and receivable 120 in the channel in the tumbler barrel when brought into register therewith upon suitably turning the hollow lock member; a handle mounted to turn upon the exterior of 125 the casing, said hollow rotatable lock mem- 130

ber being in line with the axis of the handle, the handle being formed to permit passage of a key; and mechanism within the casing having members respectively coupled with said hollow rotatable lock member and said handle.

2. The combination with a casing; of a tumbler barrel carried by an end wall of the casing and projecting into the interior of the casing; a hollow rotatable lock member coaxial with the tumbler barrel; a tumbler disposed longitudinally of the tumbler barrel and movable in a channel formed in and extending longitudinally of the tumbler barrel; an outwardly spring pressed holding pin carried by an inner portion of said hollow rotatable lock member and receivable in the channel in the tumbler barrel when brought into register therewith upon suitably turning the hollow lock member; and a handle mounted to turn upon the exterior of the casing, said hollow rotatable lock member being in line with the axis of the handle, the handle being formed to permit passage of a key.

3. The combination with a casing having an opening formed through an end wall thereof; of a rotatable hollow lock member in line with said opening and having an end portion within the casing; a key controlled lock having a stationary portion carried by said end wall of the casing and entering said hollow lock member and a complemental portion carried by said rotatable hollow lock member, said lock portions having holding engagement upon suitable turning movement of the hollow lock member and being freed of such holding engagement upon other turning movement of the hollow lock member; and a handle mounted to turn upon the exterior of the casing, said hollow rotatable lock member being in line with the axis of the handle, the handle being formed to permit passage of a key.

4. The combination with a casing having an opening formed through an end wall thereof; of a rotatable hollow lock member in line with said opening and having an end portion within the casing; a key controlled lock having a stationary portion carried by said casing and entering said hollow lock member and a complemental portion carried

by said rotatable hollow lock member, said lock portions having holding engagement upon suitable turning movement of the hollow lock member and being freed of such holding engagement upon other turning movement of the hollow lock member; and a handle mounted to turn upon the exterior of the casing, said hollow rotatable lock member being in line with the axis of the handle, the handle being formed to permit passage of a key.

5. The combination with a casing; of a tumbler barrel carried by an end wall of the casing; a hollow rotatable lock member journaled upon the tumbler barrel; a tumbler disposed longitudinally of the tumbler barrel and movable in a channel formed in and extending longitudinally of the tumbler barrel; an outwardly spring pressed holding pin carried by an inner portion of said hollow rotatable lock member and receivable in the channel in the tumbler barrel when brought into register therewith upon suitably turning the hollow lock member; a handle mounted to turn upon the exterior of the casing, said hollow rotatable lock member being in line with the axis of the handle, the handle being formed to permit passage of a key; and mechanism within the casing having members respectively coupled with said hollow rotatable lock member and said handle.

6. The combination with a casing having an opening formed through an end wall thereof; of a rotatable hollow lock member in line with said opening and having an end portion within the casing; a key controlled lock having a stationary portion carried by said casing and upon which said hollow lock member is journaled, and a complemental portion carried by said rotatable hollow lock member; a handle mounted to turn upon the exterior of the casing, said hollow rotatable lock member being in line with the axis of the handle, the handle being formed to permit passage of a key; and mechanism within the casing having members respectively coupled with said hollow rotatable lock member and said handle.

In witness whereof, I hereunto subscribe my name.

GEORGE L. CRAGG.
